UNITED STATES PATENT OFFICE.

WALTER L. FAIRCHILD, OF NEW YORK, N. Y.

METHOD OF SPLICING UNVULCANIZED RUBBER TUBES FOR AUTOMOBILE TIRES AND THE LIKE.

Application filed February 24, 1925. Serial No. 11,006.

To all whom it may concern:

Be it known that I, WALTER L. FAIRCHILD, a citizen of the United States, and residing at New York, in the county and State of New York; have invented certain new and useful Improvements in a Method of Splicing Unvulcanized Rubber Tubes for Automobile Tires and the like, of which the following is a specification.

10 This invention relates to a new and improved method of producing pneumatic tubes for vehicle tires and the like, and one of the objects of the invention is to provide a new and improved method of splicing together the ends of a tube of unvulcanized rubber, and mounting the valve stem therein, preparatory to the vulcanizing operation, whereby the ends of the tube and the seating of the valve stem are united into a 20 substantially homogeneous structure.

Other objects and aims of the invention more or less specific than those referred to above, will be in part obvious and in part pointed out in the course of the following 25 description of the steps and the relation of each step to one or more of the others thereof employed in carrying out my process, and the scope of protection contemplated will be indicated in the appended claims.

30 In the accompanying drawings, wherein I have shown a preferred form of embodiment of my invention:

Figure 1 is an elevational view of a section of unvulcanized rubber tubing.

35 Figure 2 is a similar view of said tube of unvulcanized rubber, illustrating the first step of the method.

40 Figure 3 is a similar view, showing the ends of the tubular structure brought together, so that they may be worked together and united by cohesion, preparatory to their being subjected to the vulcanizing process.

45 Figure 4 is a schematic view, showing the manner in which the mandrel which is employed in the preceding step illustrated in Figure 3, is removed from the interior of the tubular structure.

50 Figure 5 is a vertical cross-sectional view taken on line 5-5 of Figure 3.

55 Figure 6 is an elevational view of the tubular structure showing the valve stem inserted through the united portions of the tube.

Figure 7 is a vertical sectional view taken on the line 7-7 of Figure 6.

Figure 8 is a sectional view taken on the line 8-8 of Figure 6 on an enlarged scale, looking in the direction of the arrows.

Figure 9 is a vertical sectional view of a portion of the tube, showing the manner in 60 which a slit is provided in the end of the tube of unvulcanized rubber, and

Figure 10 is an elevational view showing schematically the manner in which the ends of the unvulcanized tube are united by the 65 employment of the mandrel.

Referring now to the drawings, wherein similar reference characters refer to similar parts throughout the several views thereof, the reference numeral 1 denotes a tube of 70 raw rubber, which has been produced in the usual operation of a tubing machine. It will be understood, of course, that prior to the manual handling of this tube, owing to its "tacky" condition, the exterior and 75 interior surfaces of the tube have been dusted with powdered soap-stone, talc, or the like, so as to prevent the undesirable cohering together of contacting surfaces.

The first operation performed on the tube, 80 such as illustrated in Figure 1, is to cut a slit 2 in the end 3 thereof, said slit being preferably cut at an angle to the radius of the tube, as indicated in Figure 9 of the drawings. When this operation has been 85 accomplished, a valve stem 4 having the usual base or flange 5, is inserted in the slotted end 3 of the tube, as indicated in Figure 3 of the drawings, a mandrel 6 being inserted in the opposite end of said tube, 90 as illustrated in Figure 2. The mandrel 6 is preferably provided with the straight cylindrical surface 7 and the tapered portion 8. The valve stem 4 is merely loosely inserted within the end 3 of the tube. 95

When these operations have been completed, the ends 3 and 9 of the tube are brought together, as illustrated in Figure 3, the end 9 being inserted within the slotted end 3. The ends of the tube, the contacting surfaces 100 of which have been cleaned so as to prevent free cohesion, are then thoroughly kneaded, using the mandrel as a base, so that all the contacting surfaces cohere. The parts of the tube, however, in the vicinity of the slit 2, are not kneaded together, said slit being left open, so that when the kneading operation is completed, the mandrel 4 may be removed through said slit, as indicated in Figure 4. Before the removal of the mandrel, 110

however, a circular aperture 10 has been cut by means of a circular punch in the united ends of the tube, as illustrated in Figure 3.

5 The valve stem 4 is then worked forwardly, and the end thereof projected outwardly through the aperture 10, so that the flange or base 5 surrounds the aperture 10 within the tubular structure. The next operation is to provide a base patch 11, having a central aperture, and push this base patch downwardly over the valve stem 4, bringing it in contact with the outer surface of the united ends of the tube. In this connection 10 it may be noted that this base patch is composed of laminated layers of frictioned and unvulcanized rubber, the end surface of said base patch being in a "tacky" condition, so that the base patch may be united to the 15 surface of the tube which it overlies by a kneading operation. Assuming the base patch to have been positioned on the tube as indicated in Figures 6 and 8, the aforementioned kneading operation is accomplished 20 whereby all the contacting parts of the unvulcanized rubber are united by cohesive action.

It will be noted that the valve stem 4 adjacent to the base 5 is provided with a 25 channel 13, and that the aperture 10 cut into the united ends of the tube is of smaller diameter than that of the valve stem proper, so that when the tube and base patch 12 are brought into operative relation the edges of 30 their respective apertures closely hug the channelled portion 13 of the valve stem.

The tube is now ready to be subjected to the vulcanizing operation which operation 35 unites all of the cohesively united parts into 40 a homogeneous structure surrounding the neck of the valve stem.

The slit 2 will during this operation have been closed and the meeting edges 14 and 15 brought together so that they will be united 45 by the aforesaid kneading operation. In this connection it will be seen that the cutting of this slit 2 at an angle the axis of the tube as indicated in Figure 9 facilitates the unity of the edges of the slit.

50 It will be accordingly seen I have provided a method of uniting the ends of a pneumatic tube formed of unvulcanized rubber, and mounting therein the valve stem which may be carried out in an exceedingly 55 simple manner. The operation may also be carried on more expeditiously than have been carried on similar methods as hitherto practiced.

As many changes could be made in this 60 construction without departing from the scope of the following claims, it is intended that all matter contained in the above description or shown in the accompanying drawing shall be interpreted as illustrative only and not in a limiting sense.

Having thus described my invention, and in what manner the same may be performed, what I claim as new and desire to secure by Letters Patent is:

1. The herein described method of forming a pneumatic tube of unvulcanized rubber which consists of providing a section of said tubing of suitable length, providing a slit in one end of said section, mounting a mandrel in the other end of said section, 70 bringing said ends together in lapped relation, kneading together the lapped portions of said tube so that the lapped portions thereof are united by cohesion using said mandrel as a base, cutting an aperture 75 through the lapped ends of the tube using said mandrel as a base, removing the mandrel through said slit, inserting a valve stem through said aperture, bringing together the edges of said slit, mounting an apertured 80 base patch upon said tube so that the aperture thereof surrounds the neck of the valve stem, and then kneading said tube in the vicinity of said valve stem and slit so that 85 contacting surfaces of the wall of the tube 90 are united by cohesion.

2. The herein described process of forming a pneumatic tube, which consists of providing a section of unvulcanized rubber tubing, forming a slit in one end of said section, inserting a mandrel in the other end thereof, bringing the ends of said tube together with a portion of said slitted part thereof overlying the lapping upon the end of said 95 section containing the mandrel, kneading said tube upon said mandrel to unite by cohesion the overlying or lapped portions of the ends of the tube, cutting an aperture through the said lapped portions using said mandrel as a base for the cutting instrument, removing said mandrel through said slit, inserting a valve stem through said 100 aperture, bringing together the edges of said slit, mounting an apertured base patch upon the outer wall of said tubular structure so that the aperture of the said base patch surrounds the neck of the valve stem, and then kneading together all of the 105 contacting surfaces of the tube and slit in the vicinity of the valve stem, so that contacting 110 surfaces unite by cohesion preparatory to the vulcanizing operation.

3. The herein described process of forming a pneumatic tube, which consists of providing a section of unvulcanized rubber tubing of suitable length, providing a slit in one end of said section, mounting a mandrel in the other end of said section, inserting a valve stem loosely in the slit end of the section, bringing the ends of said section together so that the slit end overlies that end of the tube containing the mandrel, kneading the overlapping portions of the tube together using the mandrel as a base, cutting an aperture through the overlapped 115 120 125 130

portions of the tube, removing mandrel through said slit, working said valve stem forwardly and bringing the end thereof upwardly so that the base of the valve stem surrounds the aperture interiorly of the tube, bringing the edges of the said slit together, positioning an apertured base patch upon the outer wall of the overlapped ends of the tube so that the aperture thereof sur-

rounds the neck of the valve stem, and then 20 kneading said overlapped ends of the tube, base patch and meeting edges of the slit, so that all contacting engaging parts are united by cohesion preparatory to the vulcanizing operation.

15

In testimony whereof I affix my signature.

WALTER L. FAIRCHILD.
